UNITED STATES PATENT OFFICE.

JOHN W. JAYCOX, OF ELKHORN, KANSAS.

WINDMILL.

SPECIFICATION forming part of Letters Patent No. 657,420, dated September 4, 1900.

Application filed December 26, 1899. Serial No. 741,705. (No model.)

To all whom it may concern:

Be it known that I, JOHN W. JAYCOX, a citizen of the United States, residing at Elkhorn, in the county of Ellsworth and State 5 of Kansas, have invented a new and useful Windmill, of which the following is a specification.

The invention relates to improvements in windmills.

10 The object of the present invention is to improve the construction of windmills, and to provide a simple and comparatively inexpensive one in which the fans or blades will be protected or shielded from the force of the 15 wind as they come into the same, whereby a maximum power is obtained from a given force of wind.

The invention consists in the construction and novel combination and arrangement of 20 parts hereinafter fully described, illustrated in the accompanying drawings, and pointed out in the claims hereto appended.

In the drawings, Figure 1 is a perspective view of a windmill constructed in accordance 25 with this invention. Fig. 2 is a similar view, one of the vertical wind-wheels being removed. Fig. 3 is a detail view illustrating the construction of the pitman for connecting the crank of the wind-wheel shaft with 30 the pump-rod.

Like numerals of reference designate corresponding parts in all the figures of the drawings.

1 designates a tower, which may be constructed of any suitable material and upon which is mounted a support consisting of an upper tubular bearing-sleeve 2 and a series of inclined supporting-rods 3, secured at their lower ends to the tower and connected 35 at their upper ends to the outer bearing-sleeve 2, which is stationary and which is adapted to receive a rotary bearing 4, consisting of an inner tube or sleeve 5 and a pair of diverging arms 6, extending upward from 40 the sleeve 5. The inner bearing-sleeve 5 is provided with a horizontal supporting-flange 7, resting upon the upper edges of the outer stationary bearing-sleeve, and the diverging arms, which extend upward from the inner 45 rotary bearing-sleeve, are provided at their upper ends with bearings for the reception of a horizontal wind-wheel shaft 8, having a

central crank 9 and carrying a pair of opposite vertical wind-wheels 10. The crank of the wind-wheel shaft is connected with the 55 upper end of a pitman 11, which is provided at its lower end with a ball 12, arranged in a suitable socket 13 of a pump-rod 14. The wind-wheels by being located at opposite sides of the crank of the wind-wheel shaft 60 balance each other and afford a steady direct power without any side draft or strain. The tower supports a rotary frame 15, carrying a curved shield 16 and a vane 17, the shield and the vane being located at opposite sides 65 of the tower and being adapted to counter-balance each other. The rotary frame is provided with a lower bearing-ring 18, and it has central standards 19 rising therefrom and arranged in pairs at opposite sides thereof. 70 The upper ends of the standards are secured to horizontal top bars 20, arranged at opposite sides of the wind-wheel and connected at their front and rear ends by inclined braces, the front inclined braces 21 being arranged 75 opposite each other, as clearly shown in Fig. 2, and the rear inclined braces 22 and 23 being arranged at different inclinations, as hereinafter explained. The horizontal top bars have their rear ends converged and supporting the inner end of the vane, being secured to the same at the lower end thereof. The vane is supported at its upper edge by oppositely-disposed converged diagonal braces 24. The rear brace 22 extends to the lower edge 80 of the vane and the other rear brace 22 extends to the top of the same. The braces 24 are further supported by a vertical rod 25.

The wind-wheels are composed of blades secured to suitable hubs, which are fastened 90 to the shaft, and the shield 16, which is arranged in advance of the lower portions of the wheels, is secured at its top to the upper ends of the front braces 21 and the front ends of the top bars 20. The lower ends of the 95 converging braces 24 are secured to the shield at points between the ends thereof, and the bottom of the shield is attached to the rotary frame adjacent to the lower bearing-ring. The top bars of the rotary frame are secured 100 to the diverging arms of the rotary bearing.

The wind-wheels are located at opposite sides of the rotary frame, as clearly shown in Fig. 1, and the curved shield is adapted to

cover the blades of the wind-wheels as they come into the wind, and the latter does not operate on the lower portions of the wind-wheels and check the rotation of the same.

5 It will be seen that the windmill is simple and comparatively inexpensive in construction, that it is strong and durable; and that the wind-wheels balance each other and the shield is balanced by the vane. It will also be apparent that the shield is firmly supported by the rotary frame and that it is adapted to exclude the wind from the lower portions of the wind-wheels, and thereby prevent the same from being retarded by the action of the wind.

10 15 on the blades as the latter come into the wind.

What I claim is—

1. A windmill comprising a tower, a support consisting of an outer bearing-sleeve, and supporting rods, a rotary bearing provided 20 with diverging arms and having an inner rotary sleeve fitting within the said sleeve and supported by the same, a horizontal shaft journaled on the diverging arms, a rotary frame supported by the tower and connected with 25 the said arms, a shield arranged at one end of the frame, and a vane arranged at the other end of the frame and adapted to coun-

terbalance the shield, substantially as described.

2. A windmill comprising a tower, a support extending upward therefrom and having a bearing, a rotary frame mounted on the tower and composed of a lower bearing-ring, upright standards arranged in pairs, the horizontal top bars supported by the standards 35 and having their rear ends converged, the front and rear inclined braces, the rear braces being disposed at different inclinations, and the diagonal braces converging upward, a vane mounted on the frame at the back thereof, a shield arranged at the front of the frame and secured at its ends to the top and bottom of the same and to the lower ends of the diagonal braces, a rotary bearing mounted on the said support, and connected with the rotary frame, a wind-wheel shaft, and wind-wheels mounted on the shaft and located at opposite sides of the rotary frame, substantially as described.

JOHN W. JAYCOX.
